GUSTAVE WALFRID ELMWALL, OF NEW YORK, N. Y.

FOUNTAIN PEN

Application filed June 15, 1926. Serial No. 116,121.

This invention relates to writing instruments and more especially to fountain pens of the self-filling type.

It is an object of this invention to provide means whereby the construction of such instruments may be simplified and cheapened while their efficiency is substantially increased.

It is the principal purpose of this invention to provide a simplified fountain pen structure having in itself all of the improved facilities common to instruments formerly manufactured, while certain of the parts heretofore thought necessary are eliminated.

15 Fountain pens common to the prior art have commonly employed specially constructed rubber bags which must be made as an individual unit part for each pen so constructed, whereas the herein disclosed invention provides for the use of standard rubber tubing which may be cut from the manufactured product as required. Furthermore, such prior pens have in general required the manipulation of thumb latches, levers or the like, which form permanent or temporary protuberances from the pen barrel and which detract from the appearance and convenience of the same; whereas this present invention provides a pen barrel wherein no protruberances are necessary and wherein the simple manipulation of a part of the pen barrel itself accomplishes the filling of the pen or the forceful ejection of liquid therefrom if necessary for cleaning purposes or the like.

30 It is the particular purpose of this invention to provide a fountain pen which will have a cylindrical outer surface without protubance or irregularity to catch in the user's clothing, which will provide the self-filling feature which will employ standard parts which can be completely evacuated without repeated operations necessary to pens of the lever type, and which at the same time will be capable of manufacture by the use of simple machinery and with the elimination of special parts.

Referring in particular to the drawings which form a part of this specification;

40 Fig. 1 is a cross-sectional elevation of one

embodiment of my invention with the ink sack in the extended or full position.

Fig. 2 is an elevation of the embodiment shown in Fig. 1 with certain parts broken away for purposes of illustration and with the whole turned 90 degrees on its vertical axis.

The barrel body 10 is turned in its inner surface as at 11 to engage the body point 12, wherein is provided a channel 14 mounting the pen point 16, held in place by the plug 18, which is suitably grooved as at 19 to receive the feeding channel 20. The upper end of barrel body 10 is preferably threaded as at 21 to engage the end or cap portion 22, having therein an elongated recess 24 wherein the member 26 slides. Member 26 is provided with a substantially circular enlargement 28 at its lower end and it is to this portion that the upper end of ink sack 30 is secured by cementing or like operation. The stem portion, or member 26, is preferably rectangular in cross-section and is substantially wider than it is thick so that it serves as a key whereby the sack engaging portion 28 is rotated when barrel cap 22 is manipulated.

Ink sack 30 may be formed of a section from any suitable rubber tubing or like flexible conduit and has its lower end securely cemented to the babb 12^b of the portion 12 so as to communicate with channel 14.

Feeding channel 20 consists of a piece of metal grooved to substantially V shape and extends throughout the length of groove 19 in plug 18, its lower extremity curving forward slightly below the eye 17 in the pen 16 so that the ink is fed downward and forward through the eye over the pen.

The operation of the improved pen is accomplished by the simple twisting of cap 22 whose normal position is shown in Fig. 1 and whose twisted position is shown in Fig. 2. It will be noted that the stem of portion 26 sliding within the recess 24 in cap 22 compensates for the lessened length of the ink sack and for the greater length of the pen barrel as cap 22 unscrews. An inspection of Fig. 2 will show that the ink sack may be squeezed, or rather wrung, completely

free of all liquid and that a single twisting operation will free the ink sack of unclean liquid and of air producing a complete evacuation for refilling which will thus be made complete without repeated manipulation.

Manifestly many changes and modifications may be made in my simplified structure as an instance of which may be cited the substitution of a pen or other marking, drawing, or painting, device well-known to those skilled in the art in the place of pen 16; all of this within the scope of my invention and within the spirit of the appended claim.

What I claim is:

15 In a fountain pen of the self filling type, a one-piece body barrel internally threaded at its upper end, a point portion affixed to the lower end of said body barrel having pen mounting and feeding means thereon, a cap 20 portion externally threaded and engaging the thread in said body barrel, said cap having a longitudinal bore therein having flat sides, a flat sided solid key engaged with the recess in said cap to turn therewith and to 25 slide without restraint in either axial direction longitudinally therein when the cap is rotated, a flexible open ended tube ink sack having one of its ends secured to the upper end of said point portion and the other end 30 to the lower extremity of said key portion whereby rotation of said cap screws the same on the aforesaid threads without disengagement to simultaneously twist the said tube 35 sack to squeeze the same without longitudinal stretch.

Signed at New York, New York, this 1st day of June, 1926.

GUSTAVE WALFRID ELMWALL.
